ATTORNEY.

UNITED STATES PATENT OFFICE.

FRANK WILSON, SR., OF LOS ANGELES, CALIFORNIA, ASSIGNOR TO ANNIE WILSON REBOUL, OF LOS ANGELES, CALIFORNIA.

RAIL AND TIE CLAMP.

Application filed October 3, 1927. Serial No. 223,653.

My invention relates to a clamp device, for use in railway construction and the like, which is an improvement on the device shown in my pending application for a patent on a railway and tie clamp, filed May 3, 1927, under Serial No. 188,580.

The primary object of my invention is to provide an improved rail and tie clamp, for holding a rail securely and rigidly bound to a tie, while serving as a resting plate for the rail and a protection for the tie, so that the former can not cut into the latter and induce decay therein.

A further object is to provide a rail and tie clamp, of the character described, which will facilitate railroad building and will materially reduce the labor involved therein.

Other objects and advantages will appear hereinafter and while I show herewith and will describe a preferred form of construction, I desire it to be understood that I do not limit my invention to such preferred form but that various changes and adaptations may be made therein without departing 25 from the spirit of my invention as herein-after claimed.

A practical embodiment of my invention is illustrated in the accompanying drawings in which,

30 Fig. 1 is a fragmentary plan view of a railway having my improved rail and tie clamp used in its construction.

Fig. 2 is a similar view of railway having a slightly modified form of rail and tie clamp from the preferred form shown in Fig. 1.

Fig. 3 is an enlarged end view of one of the ties and a fragment of rail secured thereto by my preferred form of clamp.

40 Fig. 4 is a sectional view of the rail showing the clamp as seen at right angles to the position shown in Fig. 3.

Fig. 5 is a view in perspective of the U-bolt which forms a part of my preferred 45 rail and tie clamp.

Fig. 6 is a view in perspective of the plate member of my improved clamp.

As in the former application, my improved clamp is shown as used with rails 50 10 and wooden ties 11 of the types generally employed in railroad building, and the clamp similarly consists of a plate member 12 made of plate metal of sufficient thickness and stiffness to insure the necessary 55 rigidity, and a U-bolt 13 large enough to

embrace the tie diagonally. The plate member in the present case, however, is made relatively wider than in the former case and the connecting bar 14 of the U-bolt is made correspondingly longer so that the 60 arms 15 thereof are spaced somewhat further apart.

The plate is cut longitudinally, at each end, and diagonally opposite corners are bent to form vertical lugs 16, alternately with straight lugs 17 left on the other diagonally opposite corners thereof. Holes 18, spaced to receive the ends of arms 15, are made in lugs 17 and slots 19, adapted to receive the flanges of the rail are cut in lugs 16. A 70 short longitudinal cut is made in the middle of the plate and two somewhat longer parallel transverse cuts are made therein, at the ends of the short longitudinal one, so as to leave solid flanges 20 on opposite sides 75 of the plate. The cut-a-way parts in the middle of the plate, are then bent upwardly and inwardly toward each other to form a pair of complementary offset lugs 21 which stand above the plane of the plate so that 80 gaps 22, coinciding with slots 19, are formed between lugs 21 and the plate proper.

In the process of building a railroad the ties are laid in place with U-bolts 13 thereunder, in approximately their proper positions. A suitable number of the plate members 12 are then strung on the ends of the rails, the flanges of the latter passing through slots 19 and under lugs 21 of the former, and are shifted into properly spaced 90 positions to correspond with the ties. As the rails are laid on the ties the ends of the U-bolt arms 15 are guided through holes 18 in the plate members and nuts 23 are turned on and tightened up as soon as the rails are 95 properly spaced and aligned. After the nuts have been thoroughly tightened the ends of the U-bolts are battered to prevent their turning backward or becoming loose from the vibrations incident to traffic.

100 The modified form of clamp shown in Fig. 2 consists of a modified plate member only, with which the usual form of railroad spikes 26 are intended to be used. The plate is made similar to the one shown in Fig. 6, 105 except that lugs 17 are omitted.

It will be seen that the offset lugs 21 of my improved clamp cooperate with vertical lugs 16, in gripping the flanges 27 of the rail, and vertical lugs 16 extend high enough 110

to serve as braces on both sides of the rail, so that when the plate member is secured to the tie, by means of the U-bolt 13, no lifting or tripping of the rail is possible. The main advantage of my present rail and tie clamp over the former one is that it eliminates the necessity for drilling holes in the rail flanges to receive the ends of the U-bolts and it is more reliable because of the offset lugs 21.

Having thus illustrated and described my invention I claim:

1. A rail and tie clamp comprising a plate member adapted to be placed between a rail and a tie; a U-bolt adapted to embrace a tie cooperatively with said plate member; offset lugs formed in the middle of said plate member, adapted to grip the flanges of a rail, and diagonally opposite vertical lugs

on said plate member, adapted to brace both sides of a rail and to grip the flanges of a rail cooperatively with said offset lugs.

2. A rail and tie clamp comprising a plate member adapted to be placed between a rail and a tie; said plate member having holes in diagonally opposite corners thereof; a U-bolt adapted to embrace a tie with its ends projecting upwardly through the holes in said plate member; a pair of complementary offset lugs in the middle of said plate member, adapted to grip the flanges of a rail, and a pair of complementary vertical lugs, on diagonally opposite corners of said plate member, adapted to brace both sides of the rail and to grip both rail flanges, cooperatively with said offset lugs.

FRANK WILSON, SR.
